REGULATION OF FURNACE ELECTRODES

Application filed September 30, 1926, Serial No. 138,745, and in Germany October 16, 1925.

This invention pertains to the construction and operation of electric furnaces and has to do particularly with regulation of the feed of the electrodes.

5 A general object of the invention is to increase the certainty and accuracy of the control or regulation of the feed of the electrodes.

10 Another object is the simplification of the electrode adjusting and regulating mechanism.

15 A specific object is the provision of a method and apparatus for regulating the feed of the electrodes, which afford desirable safeguards against over-adjustment.

20 Another specific object is the provision of a method and apparatus whereby the feed of the electrodes may be controlled automatically from the load of the furnace without danger of over-adjustment.

25 Another object is the provision of a method and apparatus whereby the feed of the electrodes may be controlled automatically with accuracy, irrespective of the variations in weight resulting from their wearing away in use. Other and further objects will be pointed out or indicated hereinafter, or will be apparent to one skilled in the art upon an understanding of the invention or 30 its employment in practice.

35 For the purpose of illustrating the invention generally, I disclose herein certain arrangements and apparatus wherein it may be embodied and practiced, but it is to be understood that these examples are not to be accorded any interpretation having the effect of limiting the claims short of the true and most comprehensive scope of the invention in the art.

40 In the drawing forming a part of this specification,

Fig. 1 is a diagrammatic illustration of a furnace and a single electrode and adjusting and regulating gear for the latter, the same being in the nature of a part sectional elevation, and

Fig. 2 is a section of a flow control valve for the hydraulic electrode operating means.

45 Hydraulic operation of the electrodes of electric furnaces possesses recognized advan-

tages, but heretofore has involved certain difficulties in the direction of accurate control and regulation, particularly with regard to over-adjustment. Of the hydraulic operating mechanisms, those employing a 55 single acting power cylinder, whereby the electrode is raised by hydraulic pressure and lowered by gravity, possess certain advantages in the direction of simplicity and economy over the type in which a double acting 60 power cylinder is employed. The automatic regulation of feed of the electrode in the type wherein it is lowered by gravity has involved inaccuracies, however, due to the fact that the weight of the electrode gradually decreases incident to operation of the furnace, with a resulting tendency for the rate of feed to decrease as the weight of the electrode decreases. Consequently, automatic 65 regulation between the times when the electrode is of maximum length and weight and when it is of minimum length and weight has involved complications necessary to avoid overrunning under the conditions first mentioned and insufficient feed under the last- 70 mentioned conditions. The present invention satisfactorily solves the difficulties presented by these circumstances, in the manner 75 illustrated by the example shown in the accompanying drawing.

80 Referring to the drawing, let it be understood that the reference numeral 10 designates the furnace and 11 one of the electrodes which is carried by an arm or holder 12 supported and vertically adjustable on the guides 14. The electrode is supplied with current from line 15 through a flexible cable connection 16 which accommodates the vertical adjustment of the electrode. The power cylinder 17 contains the piston 18 which is connected to the arm 12, so that the arm may be moved upwardly on the guides 14 by hydraulic power applied below the piston. The pressure-transmitting liquid is supplied from a suitable accumulator by the pipe 19 to a regulating valve cylinder 20, from which it is led to the power cylinder 17 through the pipe 21. The regulating valve 22 is adjustable to regulate the supply of pressure medium from 90 95 100

pipe 19 to pipe 21, or the exhaust from pipe 21 to pipe 24. The position of valve 22 is in turn regulated by an automatic regulator 25 in accordance with the load taken by the electrode, the same being rendered effective on the regulator through the medium of the transformer 26. Gravity tends to feed the electrode downwardly, and the rate at which it is lowered is dependent upon the rate at which the pressure medium is permitted to exhaust through pipe 24.

In the pressure line between the power cylinder 17 and regulating valve cylinder 20 I place a control device 27 which is illustrated in detail in Fig. 2. This is in the nature of a throttling valve which opens fully under pressure from pressure medium flowing through line 21 from valve cylinder 20, and partially closes under pressure of fluid flowing in the opposite direction. The valve is designated by the reference character 28 and has a guide portion 29 and cooperates with a seat 30. An adjustable member 31 determines the extent to which the valve 28 may close. The member 31 may be arranged for adjustment by hand, or otherwise.

In operation, when the adjustment of the regulating valve 22 is such as to admit pressure medium to the power cylinder 17, the control valve 28 opens fully so that the hydraulic pressure is rendered fully effective against the piston 18 in opposition to the weight of the electrode and its holder. Consequently, the lowering of the electrode may be stopped immediately upon action of the regulator 25. When the adjustment of the regulating valve 22 is such as to permit flow of pressure medium from power cylinder 17, control valve 28 occupies its partially closed position, thus throttling the flow of pressure medium from the power cylinder. In this manner a certain back pressure is produced in the cylinder from the weight of the electrode and its traveling support, which back pressure retards the descent of the electrode, the retardation being proportional to the effective weight imposed by the electrode and its traveling support upon the piston 18. As a consequence, it is not necessary to counterbalance the electrode and its carrier, and the regulation of the downward feed of the electrode by the regulating valve may be accomplished with greater uniformity and accuracy and more closely in accordance with load variations on the furnace than is possible when the weight of the electrode and its carrying frame is permitted to exercise a more variable effect on the rate at which the pressure medium is exhausted. Other important advantages attained by the invention and resulting from the fact that it makes it possible to dispense with balance weights for the electrode are the

resulting decrease in the size of the furnace and the weight of moving parts, with resulting economies in original and operating costs, and possibility of much closer regulation, due to the elimination of weight in moving parts and a consequent decrease of work requisite for their acceleration. Because of the elimination of the counterbalancing weight, the net effect, in weight differential on the piston, is not nearly so great as when the weight of the electrode and its carrier frame is counterbalanced. Consequently, by setting the throttle valve for the conditions obtaining when the electrode is half consumed, satisfactory operation over the whole range of adjustment is assured.

I claim:

1. In an electric furnace, the combination with a movable electrode carrier and an electrode mounted thereon, of a power cylinder for controlling the position of the carrier, a regulating device responsive to variations in the electrical power taken by the electrode for regulating flow of liquid under pressure to and from the cylinder, and a throttling device in the supply line between the power cylinder and regulating device, said throttling device opening under pressure of liquid flowing to the power cylinder and partially closing under pressure of liquid flowing from the power cylinder.

2. In an electric furnace, the combination with a movable electrode carrier and an electrode mounted thereon, a power cylinder for controlling movement of the carrier, means for supplying liquid under pressure to the power cylinder against the weight of the carrier and electrode, a regulating device for regulating flow of pressure medium to and from the power cylinder, a throttling device in the supply line between the power cylinder and regulating device, said throttling device being operable to close by liquid pressure from the power cylinder, and adjustable means for limiting closing movement of the throttling device.

3. In an electric furnace, the combination with a movable electrode carrier and an electrode mounted thereon, of a power cylinder for controlling adjustment of the carrier, means for supplying pressure medium to the power cylinder, regulating means for regulating flow of pressure medium to and from the power cylinder, a non-return valve in the supply line between the regulating means and power cylinder, and adjustable means for limiting closing movement of the non-return valve.

4. In an electric furnace, a movable electrode, means controlling movement of said electrode, means governing controlling action of said control means, means connecting said controlling means and said governing means and means comprising a check valve

in said connecting means for modifying the controlling action of said control means.

5. In an electric furnace, a movable electrode, means controlling movement of said electrode, means governing controlling action of said control means, means connecting said controlling means and said governing means a check valve in said connecting means for modifying the controlling action of said 10 control means, and means for preventing complete closure of said valve.

In testimony whereof I have hereunto subscribed my name at Zurich, Switzerland, this 18th day of September, A. D. 1926.
